UNITED STATES PATENT OFFICE.

ELEAZER KEMPSHALL, OF NEWTON, MASSACHUSETTS, ASSIGNOR, BY MESNE ASSIGNMENTS, TO THE RUBBER TIRE COMPANY OF AMERICA, OF NEW YORK, N. Y.

DESIGN FOR A LUG FOR VEHICLE-TIRES.

SPECIFICATION forming part of Design No. 33,249, dated September 25, 1900.

Application filed August 22, 1899. Serial No. 728,130. Term of patent 14 years.

To all whom it may concern:

Be it known that I, ELEAZER KEMPSHALL, of Newton, in the county of Middlesex and State of Massachusetts, have invented and produced a certain new and original Design for a Lug for Vehicle-Tires, of which the following is a specification, reference being had to the accompanying drawings, forming a part thereof.

10 This invention relates to a new and useful design for lugs for vehicle-tires, and it consists in the novel features of shape and configuration hereinafter fully described and particularly claimed, and clearly illustrated in the drawings.

15 Reference is to be had to the accompanying sheet of drawings, forming a part of this specification, in which like characters indicate like parts wherever they occur.

20 Figure 1 is a perspective view showing my

design. Fig. 2 is a vertical sectional view of the same.

1 represents a lug having a central aperture 2. The lug 1 is formed at one end with a flange 3, and the side of the lug at the opposite end is formed with a boss 4.

The leading feature of my design consists of a flanged lug having a laterally-extending boss upon the end opposite the flange.

I claim—

30 The design for a lug for vehicle-tires substantially as shown and described.

In testimony whereof I have affixed my signature in presence of two witnesses.

ELEAZER KEMPSHALL.

Witnesses:

H. L. ROBBINS,
E. BATCHELDER.
